ANTIPICK LOCK

Raymond Schlabauch, Millersburg, Ohio

Application May 2, 1951, Serial No. 224,159

3 Claims. (Cl. 70—421)

The present invention relates to an anti-pick lock and it consists in the combinations, constructions and arrangements of parts herein described and claimed.

Generally there is provided a lock wherein is located a cylinder which is revoluble by means of a key which is capable of moving a plate tumbler having a laterally extending tooth at its outer end which tooth is adapted to engage in a notch in a lever. A square pin is mounted in parallel relation to the axis of the cylinder and is carried by a radially extending arm which is affixed to the cylinder. There is also provided a lever having a gate in one end for the reception of the square pin and there is also provided a pivotally mounted holding lever which is normally spring-pressed toward the lever. The construction is such that when the cylinder is turned the tooth of the plate tumbler is removed from the notch in the lever making it impossible to move the latter and to "reel out" the gate therein if the square pin does not enter the same.

It is accordingly an object of the invention to provide a lock of the character set forth which is relatively simple in construction, easy to manufacture and yet effective and efficient in use.

Another object of the invention is to provide an anti-pick lock.

Other and further objects of the invention will become apparent from a reading of the following specification taken in conjunction with the drawing, in which:

Figure 1 is a vertical longitudinal sectional view of an embodiment of the invention;

Figure 2 is a plan view thereof;

Figure 3 is a sectional view of Figure 1, showing the device with a proper key therein and in unlocked position;

Figure 4 is a sectional view taken along line 4—4 of Figure 1 with key removed showing the device in normal locked position;

Figure 5 is a view similar to Figures 3 and 4 but showing the device with a wrong key inserted therein;

Figure 6 is a sectional view taken along line 6—6 of Figure 1 with key removed;

Figure 7 is a fragmentary vertical sectional view of a modification of the invention, and

Figure 8 is a sectional view taken along line 8—8 of Figure 7.

Referring more particularly to the drawing, there is shown therein a conventional lock plate 10 having a slot 11.

The mechanism comprising the present invention is best illustrated in Figure 4 and consists of a cylinder 12 having a key slot 13. The cylinder 12 is revolubly mounted in a block 25 attached by screws 28 to the rear of the plate 10. Diametrically disposed in the cylinder 12 and extending slidably upwardly therefrom is a plate tumbler 14 whose upper end has integrally formed therewith a horizontally extending tooth 15. There is also provided a lever 16 having a horizontally extending gate 16a in its upper portion and an interlocking notch 17 in its lower portion. The lever 16 is pivotally mounted at its outer end upon a pin 26 mounted in the block 25.

Affixed to the cylinder 12 is a radially extending arm 18 to the outer end of which is affixed a pin 19 which extends in a direction parallel to the axis of the cylinder 12 and which pin 19 is preferably square in cross sectional area. A holding lever 20 is pivotally mounted upon a pin 21 carried by the block 25 adjacent the cylinder 12 and a spring 22 is affixed by a screw 27 to the block 25 and bears against the outer side of the holding lever 20 and is adapted to urge the same toward the lever 16.

A longitudinal groove 30 is formed in the block 25 immediately below and a like groove 31 immediately above the cylinder 12. A secondary tumbler 32a of a

2

length equal to the diameter of the cylinder 12 is slidably disposed in a diametrically extending slot 32 in the cylinder 12 in longitudinal registry with the tumbler 14. The tumbler 32a is likewise provided with a key slot.

It will be seen that the above-described mechanism may be repeated as many times as desired, three repetitions being shown in the instant case.

In operation, it will be apparent that when a proper key is inserted through the key slots in the elements 14 and 32a that firstly the secondary tumblers 32a will be lifted so that their upper and lower ends register with the adjacent peripheral edge of the cylinder 12 and out of either of the grooves 30 or 31. At the same time it will be noted that the tumblers 14 will be raised a proper height to allow the pin 19 to enter the gate 16a when the cylinder 12 is turned in a clockwise direction as viewed, for example, in Figures 3 to 5, inclusive. At this time, it will be noted that the holding lever 20 will act to maintain the lever 16 in such lifted position during the turning of the cylinder 12 as aforesaid. In the event that a false key be inserted through the various key slots, then in that event certain of the tumblers 14 will either be raised too great a distance or be allowed to drop to an improper distance with relation, for example, to the center of the cylinder 12. In such case, as is well illustrated in Figure 5, one or more of the levers 16 will have its gate 16a out of registry with the pin 19 and hence the pin 19 will be unable to enter the gate 16a of its associated lever 16, and, of course, it will be impossible to unlock the device. It will also be apparent that when the key is removed from the device it becomes impossible to "feel out" the gate 16a if the pin 19 is abutting against the free end of the lever 16 as shown in Figure 5. In Figures 7 and 8 there is shown an identical construction with the exception that the key 36 shown therein is provided with teeth on both of its edges instead of upon one edge as is shown in Figure 1. The operation of this form of the invention is identical with that above described, the elements 14 and 32a still being lifted to particular heights by the positioning of such key in the slots.

While but two forms of the invention have been shown and described herein, it will be readily apparent to those skilled in the art that many minor modifications may be made without departing from the spirit of the invention or the scope of the appended claims.

What is claimed is:

1. A device of the character described comprising a block, a cylinder revolubly mounted in said block, said block having a longitudinal groove immediately above and a like groove immediately below said cylinder, a first tumbler diametrically disposed and vertically slidable in said cylinder and extending upwardly therefrom, a laterally extending tooth affixed to the upper end of said first tumbler, a lever pivoted at one of its ends to said block and having an inwardly extending gate formed in the upper portion of its other end and a notch for receiving said tooth in the lower portion of said other end, a secondary tumbler of a length equal to the diameter of said cylinder diametrically slidable in said cylinder in longitudinal registry with said first tumbler, said tumblers each provided with a key slot, a longitudinally extending pin carried fixedly by said cylinder in spaced relation thereto and receivable in said gate when said lever is raised to proper height, and yieldable means for maintaining said lever in raised position.

2. A device as defined in claim 1 wherein there is provided multiples of the lever and tumblers.

3. A device as defined in claim 1 wherein said means comprises an arm pivoted to said block and having its free end disposed to abut the free end of said lever, and a spring affixed to said block and bearing against said arm to urge the same into such abutting relationship with said lever.
